(57) **CLAIM**

The ornamental design for a nasopharyngeal swab, as shown and described.

DESCRIPTION

FIG. 1 is a front left perspective view of a nasopharyngeal swab showing our new design;

FIG. 2 is an enlarged view thereof;

FIG. 3 is a left elevation view thereof;

FIG. 4 is a right elevation view thereof;

FIG. 5 is a top plan view thereof;

FIG. 6 is a bottom plan view thereof;

FIG. 7 is a front elevation view thereof; and,

FIG. 8 is a rear elevation view thereof.

The broken lines shown in FIGS. 1-8 illustrate portions of the nasopharyngeal swab that form no part of the claimed design.
